Inventor:

UNITED STATES PATENT OFFICE.

WILLIAM F. HUNT, OF NEW BRIGHTON, NEW YORK.

COALING APPARATUS.

1,240,215.

Specification of Letters Patent. Patented Sept. 18, 1917.

Application filed May 15, 1914. Serial No. 838,624.

To all whom it may concern:

Be it known that I, WILLIAM F. HUNT, a citizen of the United States, and a resident of New Brighton, county of Richmond, in the State of New York, have invented certain new and useful Improvements in Coaling Apparatus, of which the following is a specification, reference being had to the accompanying drawing, forming a part hereof.

10 The present invention is illustrated and described as embodied in coaling apparatus, but as this description proceeds it will be evident that the invention is not to be limited to the character of the material handled, 15 coal being selected for the purpose of this disclosure for the sake of convenience and as typical of the material in the handling of which arise certain problems. In transferring coal from a source of supply, as for 20 instance, a car, to another point, it is desirable to prevent breakage of the lumps of coal and pulverization thereof to as great a degree as possible. In preventing this breakage, care must be taken that the coal is not 25 subjected to sheer drops of any great extent. The improved apparatus shown herein is constructed and arranged to bring about a continuous flow of the coal on itself, from one point to another, and to prevent any 30 considerable free fall of the coal, thus preventing the breakage which always occurs when the flow is intermittent. In accomplishing the general purpose of this invention which is, as indicated above, to prevent 35 the breakage of the material, means are provided in combination with the coal carrying devices for regulating at all times automatically the position of the mouth of the discharge chute with respect to the pile of the 40 material discharged, so that, as the height of the pile increases the mouth of the chute will be raised and thus maintain at all times a substantially uniform discharge area. In this way, it becomes impossible for the coal 45 to flow intermittently by reason of the constantly changing discharge area, permitting first a relatively slow flow and then an abnormally rapid flow. This automatic control of the discharge area is facilitated 50 greatly by another feature of the present invention which resides in providing the mouth of the chute with an irregular edge, so that a graduated opening is secured as the chute is raised with respect to the top 55 of the coal pile. This graduated opening will permit unusually large lumps of coal to

flow therethrough while the other portions of the discharge area remain just sufficient to permit free flow of the average sized lump of coal. In carrying out the invention a 60 sloping chute is arranged with its upper end near the coal to be shifted and with its other end directly over the upper end of a vertically disposed telescopic chute. The first named chute is provided with devices 65 for adjusting its angularity with respect to the second named chute so that the rate of flow may be controlled at all times. The second named chute is formed of a plurality of conical sections flaring outwardly from 70 top to bottom, so as to insure a free and uninterrupted flow of the coal therethrough. The upper section of this flaring chute carries devices which are acted on by the coal within the chute to control automatically the 75 position of the mouth of the chute with respect to the pile. The devices referred to may take widely different forms, but in the embodiment illustrated they serve to control an electric hoist, this hoist operating to 80 raise the chute against the action of a weight which is carried by the chute.

The invention will be described more particularly with reference to the accompanying drawing, in which the figure represents 85 a complete apparatus embodying the present improvements, all of the elements thereof being shown in side elevation, except the weight which is shown in vertical section.

The coal to be discharged may be supposed to rest at the point indicated by the reference character *a* and flow therefrom into an inclined chute *b*, supported partially by cables *c* extending to a suitable windlass, or the like, *d*, whereby the angular position 90 of the chute with respect to the horizontal may be varied by the operator to control the rate of flow. The lower end of the chute *b* may be disposed directly over the hopper *e* of a sectional chute composed of a series 100 of telescopic sections, as *e'*, *f* and *g*. These sections may be of any desired shape and area, although they preferably flare from top to bottom along their longitudinal axis to facilitate the free flow of coal therethrough. In the illustrated embodiment, it may be supposed that the sections are tapered slightly and arranged to telescope one upon the other. The lower section *g* may 105 carry thereon a circular weight *g'* of concrete, or the like, for a purpose to be herein-after pointed out. The lower edge of the

last named section is dished at one point or some points, as indicated generally at g^2 , these dished portions taking any approved form and being arranged as the best practice requires. That is to say, the lower section g may be dished from side to side, or it may be provided with a scalloped edge, or it may have an edge of some other irregular outline, the result sought to be obtained by this irregular edge being a graduated opening through which the coal may pass as the section is raised from the top of the heap h .

During the use of the apparatus the lower section or sections of the chute are raised and lowered to maintain a reasonably uniform head in the hopper e by a suitable device controlled by the accumulation of coal in the hopper. As shown, the lower section has secured to it, as at g^3 , cables h , which are connected to a hoist i . The latter is shown as comprising an electric motor and it is proposed to control the circuit of this motor through a switch l and terminal m , the switch l and contact m preferably being mounted on a suitable skeleton frame e' fastened to the mouth or hopper e of the upper section e' of the sectional chute. The lower arm of the switch l is arranged directly in the path of the coal flowing from the inclined chute b into the telescoping tubes, while the upper arm of the switch is, of course, arranged out of the way of the coal.

In operation the coal flows through the chute b and sections e' , f and g , to the pile h , the lower edge of the section g being held in contact with the pile by the weight g' . It will be evident that the flow of coal at the start will continue until the chute is filled to the top, the spread of coal adjacent the base of the chute being relatively slight. When the coal begins to fill up the flaring mouth or hopper e of the upper section e' it will abut against the weighted switch l and move the same until its upper arm is in contact with the terminal m . The closing of this contact serves to set the hoist i in operation and the cables h are wound on the usual winding drum to an extent sufficient to raise the lower section g from the pile and permit a freer flow of coal from under the lower edge of said section, such freer flow serving to lower the level of the coal in the hopper e of the upper section e' and permit the switch l under the influence of gravity, or other suitable actuating means, to move to a position where its upper arm is out of contact with the terminal m at which time, operation of the motor will cease. The drum of the hoist is now free, so that the weight on the lower telescopic chute now causes said chute to settle into the pile of coal and impede or reduce the rate of flow at the bottom of the chute to an amount less

than the rate of flow into the hopper of the telescopic chute. The upper hopper now fills again, whereupon the operation described above will be repeated, the net result being that during the operation of the improved apparatus the flaring chute is kept substantially balanced or floating so that a uniform flow of coal is maintained automatically. It will be evident that the irregular edge of the lower section g will assist in this automatic control of the flow inasmuch as this edge affords graduated openings as the section is raised from the pile so that larger lumps of coal may pass out freely without making it necessary to increase the discharge area throughout and thus permit an abnormally free flow of the average-sized lumps of coal. It will also appear that the balancing of the flaring chute in the illustrated embodiment is accomplished through the tendency of the motor i to raise the lower section and the counteracting tendency of the weight g to hold the lower section in contact with the coal heap.

In the accompanying drawing many of the parts of the apparatus are illustrated in a purely conventional manner inasmuch as it will be evident to those skilled in the art that such parts will find a wide range of equivalents and the advantageous features of the invention still be realized by the substitution of such equivalents. While many of the desirable effects secured are referred to in the specification it should be emphasized here that the invention is primarily addressed to the provision of devices for automatically controlling the area of discharge opening so as to insure a constant and uniform flow of coal upon itself.

I claim as my invention:

1. Apparatus for transferring coal including a chute disposed in a substantially vertical position and having its lower end provided with a graduated opening for the discharge of the material.

2. Apparatus for transferring coal including a chute, means operable automatically to raise the chute when the coal rises within the chute to a predetermined height, and means tending to hold the lower edge of the chute in proximity to the top of the pile, whereby the chute changes position in accordance with the change in the height of the pile.

3. Apparatus for transferring coal including a chute, means controlled by the coal and operable thereby when the coal rises within the chute to a predetermined height to raise automatically the chute in accordance with the change of elevation of the pile.

4. Apparatus for transferring coal including a chute composed of a series of telescoping tubes, means to raise the chute, a weight secured thereto to hold the lower edge in

proximity to the coal pile, and devices operable by the coal when the coal rises within the chute to a predetermined height to control the means for raising the chute, whereby the latter is caused to change its position automatically in accordance with the increase in the elevation of the pile.

5. Apparatus for transferring coal including a chute composed of a series of telescoping tubes, hoisting cables attached to the lower section of the chute, a hoist for operating said cables, and means to control the operation of the hoist, said means being

controlled by the coal in the chute so that as the amount of coal in the chute increases, 15 the hoist will be operated to cause the lower section of the chute to be raised automatically in direct substantial accordance with the increase in the elevation of the pile.

This specification signed and witnessed 20 this 12th day of May, A. D. 1914.
